R. C. BENDER

HUMIDIFIER AND DUST COLLECTOR

Filed Dec. 9, 1925

By

Inventor
Robert C. Bender
Cornwall, Bradell-Janus, ATTYS.

UNITED STATES PATENT OFFICE.

ROBERT C. BENDER, OF ST. LOUIS, MISSOURI.

HUMIDIFIER AND DUST COLLECTOR.

Application filed December 9, 1925. Serial No. 74,425.

This invention relates to new and useful improvements in humidifiers and dust collectors for dwellings, and particularly when used with registers in hot air heating systems.

The objects of the invention are to provide a humidifier which can be readily attached to the register and which is so constructed that it occupies very little space and is adjustable for use in connection with registers of various constructions.

Further objects of the invention are to provide humidifiers and dust collectors which are neat in appearance, can be easily cleaned and refilled with clean water and are provided with means for inducing the air to circulate therethrough, thereby causing the hot air to heat the water contained therein and mix with the moisture produced by the evaporation of water so that the air of the room in which the humidifier is located is maintained at the proper degree of humidity and is kept free of dust which is separated from the air and deposited in said humidifier.

With these and other objects in view, my invention consists in certain novel features of construction and arrangement of parts, hereinafter more fully described and claimed, and illustrated in the accompanying drawings, in which—

Figure 1 is a front elevational view of a humidifier attached to a register.

Figure 2 is a plan view of the same.

Figure 3 is an enlarged end elevational view with a portion of the register shown in section.

Figure 4 is an enlarged vertical cross section taken on line 4—4 of Figure 1.

Figure 5 is a section taken on line 5—5 of Figure 3.

Figure 6 is a cross section taken on line 6—6 of Figure 3.

Referring by numerals to the accompanying drawings, 10 indicates a wall register of a hot air heating system and arranged above said register is an open top casing 11 which is approximately of the same length as the register and is comparatively narrow in width so as to occupy very little space when in position. The rear wall 12 of the casing is disposed vertically and is adapted to be placed against the wall of the room.

The front wall 13 of the casing is inclined from vertical so as to overhang the register 10 and is provided with a plurality of openings 14 through which the air discharged by the register is admitted into the casing. These openings are preferably formed by striking or bending portions of the wall outwardly to form deflector plates 15 which serve to increase the circulation of air through the casing.

The end walls 16 of the casing are provided with elongated openings 17 which also serve to permit admission of air within the casing.

A container or pan 18 is arranged within casing 11 and rests on a pad of asbestos or other absorbent material 19. This pad acts as a cushion for a container 18 and absorbs the moisture formed in the casing by condensation or otherwise introduced therein. Container 18 is of smaller dimensions than the casing 11 so that it is spaced from the front and end walls of the casing a suitable distance to permit air admitted into the casing to come in contact with the walls of said container, thereby heating the water contained therein and producing evaporation thereof.

The upper end of casing 11 is closed by a top 20 having downwardly presented marginal flanges 21 which fit against the edges of casing 11 and serve to hold said cover in place. This cover is provided with a series of openings 22 through which the air is discharged from the casing 11. Container 18 terminates a suitable distance below the top of casing 11 in order to provide a mixing chamber wherein the air and the vapor are mixed before being discharged from the casing. Container 18 is provided with suitable hand holes 18^a by means of which the container can be readily removed from the casing.

In addition to deflector plates 15, an apron or extension 24 may be used to deflect the air discharged by the register toward the casing, if so desired. This extension is hinged at 25 to a hook 26 so that said extension may be folded upwardly out of the way as shown in dotted lines in Figure 3. A hook 26 is provided on each side of extension 24 and is detachably seated in a seat or socket 27 formed in the wall 13 of casing 11.

Casing 11 is held in position by having its bottom wall resting on the frame or projecting portion of the register as shown in Figure 3 and by attaching means 28 which are adapted to be secured to the grille or grating 10^a of register 10. Attaching means 28 comprises a U-shape member 29, the parallel portions 30 of which are slotted and are adjustably secured to vertically disposed bars 31 which are attached to the end walls 16 of casing 11 and extend a suitable distance below the same. Slotted portions 30 are attached to bars 31 by means of thumb screws 32 whereby member 29 may be shifted in a vertical plane relative to casing 11 and can be disposed at an angle to bars 31 with thumb screws 32 being used as pivots.

U-shaped clips 34 removably engage the horizontal portion 29^a of member 29 and have depending legs 35 which are adapted to be placed against the outer side of grille 10^a. A screw 36 is carried by each member 35 and is screw-seated in a member 37 which is removably disposed on the opposite side of grille 10^a so that by tightening screw 36 a portion of grille 10^a is clamped between members 35 and 37, thereby securing member 29 rigidly in position. The vertical adjustment of member 29 permits disposition of clamping members 35 and 37 at a suitable point on the grille of the register and the angular adjustment of member 29 enables the attaching of member 29 to registers having their gratings or grilles disposed at various angles.

Bars 31 may be slotted vertically and the slotted portions of members 30 may be bent at right angles to provide for wider range of adjustments. Thumb screws 32 engage nuts 38, and lock washers 39 may be used to hold the parts against displacement. The bottom of container 18 is preferably made to fit snugly within the casing 11 and the walls of the container are arranged angularly to the corresponding walls of the container in order to provide air space between the respective walls and allow circulation of air therebetween. Container 18 may be removed for cleaning purposes and refilled with fresh water. Similarly, casing 11 can be detached from supporting means by unscrewing thumb screws 32 whereupon said casing can be cleaned and if necessary pad 19 replaced by a new one. Casing 11 and top or cover 20 can be made in any desired finish so as to harmonize with the register and can be of any suitable design or shape.

My improved humidifier is simple in construction, can be easily cleaned and supplies the air with the proper amount of moisture necessary to maintain the rooms in healthful condition.

While I have shown the preferred form of my invention, it is obvious that my de-

vice is susceptible to various modifications and changes without departing from the spirit of my invention.

I claim:

1. A humidifier for hot air heating systems comprising a casing adapted to be secured adjacent to and transversely of the hot air discharge opening, said casing being provided with a plurality of openings for permitting circulation of air therethrough, a water container arranged in said casing and spaced from the walls thereof and heated by the air circulated through the spaces thus formed whereby the air is mixed with the vapors produced thereby before being discharged from said casing, and means attachable to a hot air register for supporting said humidifier above the latter. 70

2. A humidifier for hot air heating systems comprising a casing adapted to be secured adjacent to the hot air discharge opening, said casing being provided with a plurality of openings for permitting circulation of air therethrough, a water container arranged in said casing and heated by the air circulated therethrough whereby the air is mixed with the vapors produced thereby before being discharged from said casing, and supporting means for said casing, said supporting means being adjustable in vertical 90 plane and angularly relative to said casing. 95

3. A humidifier for hot air registers comprising a casing, a support adapted to be attached to a hot air register, means for adjustably mounting said casing on said support, and a water container in said casing, there being openings formed in the walls of said casing for causing hot air discharged from the register to circulate through said casing and around said water container, 105 thereby heating the water container therein, there being a chamber arranged between the top of said casing and said water container for permitting air to mix with the water vapors before being discharged from said 110 casing.

4. A humidifier and dust collector for hot air registers comprising an open top casing adapted to be placed against the wall and above a hot air register, means for adjustably attaching said casing to said hot air register, a water container removably arranged within said casing and spaced from the walls thereof, said casing being provided with perforated walls for permitting hot air to enter said casing, and a perforate removable cover for said casing for discharging hot air and vapor from said casing. 115 120

5. A humidifier and dust collector comprising an open top casing adapted to be detachably secured to and disposed above a hot air wall register, said casing having its front wall inclined from vertical and overhanging said register, there being a series of openings formed in said inclined wall 125 130

to admit hot air into said casing, a pan of absorbent material arranged in the bottom of said casing, a water container arranged within said casing and spaced from the walls thereof, and a perforated cover for closing the upper end of said casing.

6. A humidifier for hot air heating systems comprising a casing adapted to be secured adjacent to the hot air discharge opening, said casing being provided with a plurality of openings for permitting circulation of air therethrough, a water container arranged in said casing and heated by the air circulated therethrough whereby the air is mixed with the vapors produced thereby by being discharged from said casing, and an extension plate secured to the front wall of the casing and overhanging the hot air register, said plate being angularly disposed relative to said wall to direct the hot air thereagainst.

7. A humidifier comprising a casing adapted to be placed against the wall of a room above the hot air discharge opening, said casing being provided with a plurality of openings for permitting circulation of air therethrough, a water container arranged in said

casing terminating a suitable distance below the top of said casing to form a mixing chamber and having its walls spaced from the walls of said casing for the passage of air therethrough, whereby the water in said container is evaporated and mixed with said air and a perforate cover for said casing.

8. A humidifier comprising a casing having its front wall inclined from the vertical and provided with a series of openings, outwardly projecting deflector plates on said wall for deflecting the air through said openings into said casing, and a water container arranged in said casing, said container having its bottom substantially of the same dimensions in one direction as the inside dimension of the bottom of said container, thereby serving to properly position the latter, the walls of said container being angularly disposed relative to the walls of the casing to provide air spaces therebetween which air spaces increase upwardly.

In testimony whereof I hereunto affix my signature this 28th day of November, 1925.

ROBERT C. BENDER.
